SPRINKLER

Allan J. Lyons, Glendale, Calif.

Application September 16, 1949, Serial No. 116,184

2 Claims. (Cl. 299—58)

1

This invention relates to a sprinkler for sprinkling laundry, and for similar purposes, and relates more particularly to a hand sprinkler which is attachable to a water faucet to receive and discharge a continuous supply of water under manual control and at a reduced pressure.

It is among the objects of the invention to provide a sprinkler assembly which can be connected to a water faucet to receive a continuous supply of water and includes means for supplying water at a pressure reduced from the pressure of the water at the faucet, which includes a hand-operated sprinkler and means for manually controlling the discharge of water from the sprinkler, and which is simple and durable in construction, easy to attach to a faucet and use, economical to manufacture, and neat and attractive in appearance.

Other objects and advantages will become apparent from a consideration of the following description and the appended claims in conjunction with the accompanying drawing, wherein:

Figure 1 is a side elevation of the sprinkler assembly of the invention shown attached to a conventional water faucet, certain parts being broken away and shown in cross-section to better illustrate the construction thereof;

Figure 2 is a transverse cross-section on an enlarged scale on the line 2—2 of Figure 1;

Figure 3 is a longitudinal cross-section on the line 3—3 of Figure 2;

Figure 4 is a longitudinal cross-section on the line 4—4 of Figure 1;

Figure 5 is a transverse cross-section on the line 5—5 of Figure 1.

With continued reference to the drawing, the numeral 10 generally indicates a conventional water faucet mounted adjacent to a sink or basin, not illustrated, provided with a drain for carrying away water discharged from the faucet.

The sprinkler assembly of the invention comprises, in general, a pressure-reducing unit 11 attachable to the faucet 10, a portable sprinkler unit 12 and a flexible conduit 13 connecting the sprinkler unit 12 to the pressure-reducing unit 11.

The pressure-reducing unit 11 comprises an elongated housing 14, preferably of cylindrical shape, having one open end and having at its opposite end an end wall 15 provided with a central opening 16 providing a by-pass surrounded by an annular flange or boss 17 at the inner side of the end wall 15. Intermediate its length, the housing 14 is provided with an internal ring 18 having an internally-screw-

2

threaded portion 19 terminated by an inwardly-extending flange 20. A circular valve plate 21 provided with peripheral screw-threads is threaded into the ring 19 and against the shoulder provided by the flange 20 and this plate is provided with a central opening surrounded by a beveled valve seat 22.

A hemispherical-shaped valve body 23 is positioned at the side of the valve plate 21 adjacent the housing end wall 15, and a coiled compression spring 24 is interposed between the valve body and the end wall of the housing to resiliently force the valve body into seating engagement with the valve seat 22. The spring 24 surrounds the internal boss 17 at one end and is received at its other end with a marginal flange 25 formed on the flat face of the hemispherical valve body 23, to maintain the spring in operative assembly with the housing and the valve body.

At the side of the ring 19 opposite the end wall 15, the cylindrical housing wall 14 is provided with an opening 26 and a tubular fitting 27 providing a discharge conduit is secured to the housing wall in registry with the opening 26 and projects outwardly from the housing wall to receive one end of the flexible conduit 13.

A sleeve 28 of resilient material, such as rubber, receives at one end the housing wall 14 at the open end of the housing and receives at its opposite end the spout of the water faucet 10 when the sprinkler assembly is operatively connected to the faucet.

If desired, suitable clamp bands may be placed around the sleeve 28 to secure the sleeve to the pressure-reducing unit 11 and to the faucet 10 with sufficient force so that the sleeve cannot be forced off of the faucet or the unit 11 forced out of the sleeve by the pressure of water necessary to move the valve body 23 away from the valve plate 21 against the force of spring 24.

The strength of spring 24, however, is such that no excessive pressure will be built up in the upper chamber of the pressure-reducing unit, 45 in the hose connection or in the sprinkler unit, and the water pressure maintained by the spring 24 is sufficiently low that a resilient rubber sleeve will not ordinarily be pulled off of the faucet or off of the pressure-reducing unit, the water will not come out of the sprinkler unit with a spurt or gush when the sprinkler valve is opened, and which is, in fact, very much lower than the pressure of the water at the faucet.

The valve body 23 will maintain a water pressure in the housing 14 between the faucet and

the valve plate 21 at a value determined by the strength of the spring 24. As soon as the water pressure between the faucet and the valve body 23 exceeds this value, the spring 24 will be partly collapsed permitting the valve body to move away from the valve seat and discharge some of the water through the opening 16 in the bottom wall of the housing, which water falls into the sink or basin below the faucet and is discharged through the usual drain connection.

The sprinkling unit 12 comprises a housing having a side wall 30 which is also preferably of cylindrical shape, and a bottom wall 31 provided with a large number of very small perforations or orifices 32. The side wall 30 is provided with external screw-threads at its end opposite the bottom wall 31 and a peripherally-flanged top wall or cover 33 is threaded onto these screw-threads. The cover 33 is provided with a centrally-located aperture boss 34 which provides a guide for a valve stem or plunger 35.

An annular ring 36 is provided in the side wall 30 intermediate the length thereof, and this ring has an internally-screw-threaded portion 37 terminating in an inwardly-extending flange 38. A circular valve plate 39 having peripheral screw-threads thereon is threaded into the ring 36 and against the shoulder provided by the flange 38, and this valve plate has a centrally-disposed opening surrounded by a beveled valve seat 40.

The valve stem 35 extends though the boss 34 inwardly of the housing of the unit 12 and a valve head 41 is secured to this valve stem at the inner end thereof, the valve head being disposed at the side of the valve plate 39 opposite the cover 33. A spring abutment 42 is fixed on the valve stem at the inner side of the cover 33, and a coiled compression spring 43 surrounds the valve stem between this abutment and the valve plate 36. The valve plate 36 is provided with an annular flange or boss 44 surrounding the opening therein and receiving the adjacent end of the spring 43 to hold this end of the spring against movement relative to the valve plate and the spring abutment 42 is provided with a marginal flange 45 receiving the opposite end of the spring. A gasket 46 is carried by the spring abutment and is compressed between the spring abutment and the cover 33 when the valve 41 is closed to prevent leakage of water through the boss 34 around the stem 35.

The outer end of the stem 35 is provided with external screw-threads and a valve knob or button 47 is threaded onto this end of the stem.

When the valve knob 47 is forced toward the cover 33, the valve head 41 will be moved away from the valve seat 40 to open the valve and permit the water to be discharged through the perforations 32 in the bottom wall 31, and when manual pressure is removed from the knob 47, the spring 43 will close the valve. The spring 43 is preferably made somewhat stronger than the spring 24, so that when the spring 43 closes the valve in the sprinkler unit, the valve in the pressure-controlling unit will be open to permit a discharge of water through the pressure-controlling unit.

The side wall 30 of the sprinkler unit is provided with an opening 48 between the cover 33 and the valve plate 39 and a tubular fitting 49 is secured to the side wall 30 in registry with the opening 48 to provide an inlet conduit and projects outwardly from the side wall 30 to receive the adjacent end of the flexible conduit 13.

The conduit 13 may be formed of any suitable,

flexible material, such as rubber, synthetic resin plastic or artificial rubber.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A sprinkler assembly for attachment to the discharge end of a spigot comprising a pressure-reducing unit having an inlet at one end and a by-pass outlet controlled by a spring-biased valve at the opposite end arranged so that the inlet end is in alignment with said spigot discharge end, a resilient sleeve carried by the discharge end of said spigot and embracing a portion of said unit adjacent the inlet end for securing said unit to said spigot discharge end, a discharge conduit extending transversely through the wall of said unit adjacent and spaced from the inlet end and secured to the unit, a flexible conduit positioned exteriorly of said discharge conduit and having one end connected to the other end of said discharge conduit, a sprinkler unit closed at both ends and provided with an inlet conduit projecting transversely from the wall of said sprinkler unit adjacent and spaced from one of the closed ends thereof positioned adjacent the other end of said flexible conduit and having its inlet conduit connected to the other end of said flexible conduit, the other closed end of said sprinkler unit being provided with a plurality of perforations, a valve seat fixedly positioned transversely of and within said sprinkler unit between and spaced from the other perforated closed end of said sprinkler unit and said inlet conduit, a valve positioned within said sprinkler unit intermediate said valve seat and said perforated end of said sprinkler unit and mounted in said unit for movement into and out of seating engagement with said valve seat, and hand actuatable means exteriorly of said one closed end of said sprinkler unit and operatively connected to said valve for effecting movement of said valve out of seating engagement with said valve seat.

2. A sprinkler assembly for attachment to a discharge end of a spigot comprising a pressure-reducing unit having an inlet at one end and a by-pass outlet controlled by a spring-biased valve at the opposite end arranged so that the inlet end is in alignment with said spigot discharge end, a resilient sleeve carried by the discharge end of said spigot and embracing a portion of said unit adjacent the inlet end for securing said unit to said spigot discharge end, a discharge conduit extending transversely through the wall of said unit adjacent to and spaced from said inlet end and secured to the unit, a flexible conduit positioned exteriorly of said discharge conduit and having one end connected to the other end of said discharge conduit, a sprinkler unit closed at both ends and provided with an inlet conduit projecting transversely from the wall of said sprinkler unit adjacent to and spaced from one of the closed ends thereof positioned adjacent the other end of said flexible conduit and having its inlet conduit connected to the other end of said flexible conduit, the other closed end of said sprinkler unit being provided with a

plurality of perforations, a valve seat fixedly positioned transversely of and within said sprinkler unit between and spaced from the other perforated closed end of said unit, and said inlet conduit, a valve positioned within said sprinkler unit intermediate said valve seat and said perforated end of said sprinkler unit and mounted in said unit for movement into and out of seating engagement with said valve seat, hand actuatable means exteriorly of said one closed end of said sprinkler unit and operatively connected to said valve for effecting movement of said valve out of seating engagement with said valve seat, and spring means operatively connected to said valve

for urging the latter into seating engagement with said valve seat.
